(57) **CLAIM**

The ornamental design for a siding splice joint, as shown and described.

DESCRIPTION

FIG. 1 is a perspective view of a siding splice joint;
FIG. 2 is a front elevation view thereof, which is a mirror
image to the back elevation view thereof;
FIG. 3 is a top plan view thereof;
FIG. 4 is a bottom plan view thereof; and,
FIG. 5 is a left side elevation view thereof, which is a mirror
image of the right side elevation view.

1 Claim, 2 Drawing Sheets

FIG. 3

FIG. 4

FIG. 5
